APPARATUS FOR LAYING UP THREAD

William H. Furness, Haddonfield, N. J., assignor
to American Rayon Company, Inc., Riverton,
N. J., a corporation of New Jersey

Application May 1, 1940, Serial No. 332,692

9 Claims. (Cl. 242—53)

This invention relates to a simple and effective apparatus for laying up thread, such as freshly spun rayon filaments, cotton yarns, and the like, for treatment.

The nature, objects and advantages of my invention will appear from the following description.

Figures 1 and 1A, showing the left and right hand end portions, together constitute a side elevational view of thread laying up apparatus embodying my invention;

Figure 2 is an end view looking toward the left in Figure 1A; and

Figures 3 and 4 are diagrammatic views illustrating how cords and pulleys employed in my apparatus are arranged.

The apparatus comprises in general a non-rotatable cage-like cylinder A, a thread laying up whorl B at one end of the cylinder, a thread taking off whorl C at the other end of the cylinder, clutch controller driving means D and E for the whorls B and C, and a main support F for the apparatus.

The cage-like cylinder A comprises in general a supporting structure or frame G, a plurality of pulleys H and J arranged in pairs at the ends of the frame G, a plurality of cross-over pulleys K located intermediate of the ends of the frame G, and a plurality of thread supporting and advancing cords L arranged over the pulleys in a manner hereinafter appearing.

The frame G is composed of end members 4 and 5, longitudinal members 6 connecting the end members, and intermediate bracing members such as indicated at 7 in Figure 1.

The pairs of pulleys H are adjustably secured to the end member 4 in pairs by means of brackets 8 having transverse rods 9 on which the pulleys are rotatably mounted in spaced relation. In this instance four brackets 8, positioned at right angles to each other, are employed. The pairs of pulleys J at the other end of the cylinder are similarly arranged and adjustably secured to the end member 5 of the frame G.

The cross-over pulleys K are secured on vertically spaced shafts 10 and 11 as viewed in Figure 1, there being two spaced pairs of pulleys 12 and 13 on the shaft 10 and two spaced pairs of pulleys 14 and 15 on the shaft 11. These pulleys are driven by means of worm wheels 16 and 17 secured on the shafts 10 and 11 respectively, the worm wheels being driven by a central worm 18 secured on a rotating axle or shaft 19. The shaft 19 is rotatably mounted in the end member 4 of the frame G and in a bearing 20 carried by said

frame. The shaft 19 is rotated by means of a gear wheel 21 secured thereon which meshes with the driving gear 22 of the driving means D.

Referring now to the thread supporting and advancing cords L, it will be seen that in this instance I employ four cords so arranged that eight longitudinal outer runs of cord are provided to constitute the thread supporting surfaces of the cylinder, the end pulleys over which the cords run being arranged so that the eight outer runs are disposed in evenly spaced circular arrangement around the axis of the cylinder.

In Figures 3 and 4 the arrangement of two of the cords is diagrammatically illustrated, it being pointed out that the remaining two cords are similarly arranged. By referring to Figure 3 and starting from the point X the cord first passes over the pulley H¹, then over the pulley J¹, then over the inner pulleys of the pairs of cross-over pulleys 12 and 14, then over the pulley H², then over the pulley J², and then over said inner cross-over pulleys 12 and 14 again to the point of beginning.

By referring to Figure 4 and starting from the point Y, the cord first passes over the pulley H³, then over the pulley J³, then over the outer pulleys of the pairs of cross-over pulleys 12 and 14, then over the pulley H⁴, then over the pulley J⁴, and then over said outer cross-over pulleys 12 and 14 again to the point of beginning.

In these figures I have indicated the direction of travel of the cords by arrows, and it is to be noted that the outer runs L¹, L², L³ and L⁴ all travel in the same direction and at the same speed, this also being the case with the outer runs of the remaining cords.

Thus I have provided a plurality of thread supporting surfaces which all move in the same direction and at the same speed with the result that as the thread is whirled onto the cylinder at the receiving end by the whorl B, it is advanced along the cylinder so as to lay up the thread in the form of a continuously advancing helix. In this instance the pulleys J are of smaller diameter than the pulleys H and are arranged somewhat closer to the center of the cylinder so that the helix reduces in diameter toward the thread taking off end.

The thread take off whorl C is rotated at the same speed as the thread laying up whorl B so that for each turn of thread laid up at one end of the cylinder a turn is taken off at the other end of the cylinder.

The cylinder A is supported at the thread receiving end by means of a pair of rollers 23, 24

on which the rim 25 of the gear wheel 21 rides, and at the thread taking off end by means of a pair of rollers 26, 27 on which the rim 28 of the gear wheel 29 rides, it being noted that the gear 29 is rotatably mounted on the axle 30 of the cylinder A, which axle is fixedly secured to the frame G by means of supports 31 secured to said frame.

It will thus be seen that the cylinder A is supported by the rollers 23, 24, 26 and 27 peripherally of the gear wheels 21 and 29. This mounting of the cylinder is of importance because since the thread is laid onto one end of the stationary cylinder by means of the whorl B secured to the rotating gear wheel 21, and is taken off the other end of the cylinder by means of the whorl C secured to the gear wheel 29, the mounting means must be so arranged that there will be no interference with, or obstruction in the path of the whirling run of thread leading to and away from the rotating whorls.

The thread T is led from a suitable source, such as a spinneret, to the cylinder A by first being passed through a fixed guide 32 located in spaced coaxial relation to the end of the cylinder, then through a slot 33 at the periphery of the gear wheel 21, then through the whorl B and finally to the cylinder. In initially starting the laying up of a run of thread on the cylinder, the end thereof is merely laid onto the supporting cords of the cylinder preferably by wrapping it around the cylinder one or two turns, and when this end has been advanced to the take-off end of the cylinder it is threaded through the take-off whorl C, then through a slot 34 at the periphery of the gear wheel 29, then through a fixed guide 35 located in spaced coaxial relation to the end of the cylinder, and from thence it may be led to a spool or other suitable receiving device. During this operation of laying up a new run of thread on the cylinder the clutch of the driving means D is engaged to cause rotation of the whorl B and the clutch of the driving means E is disengaged so that the take-off whorl C remains stationary to facilitate passing the thread through it and the guides which lead to the thread receiving device. When the feed of thread is cut off to complete a particular run, the clutch of the driving device D may be disengaged while the clutch of the driving device E remains engaged to take-off the thread which is on the cylinder A.

In order to positively hold the cylinder against rotation and yet not interfere with the whirling thread I have provided a holding device S at one end of the cylinder, in this instance at the thread take-off end. This device comprises a reciprocable diametral bar 36 mounted in a guide 37 which is secured to the non-rotatable axle 30 of the cylinder, fixed supports 38 and 39 located at the end of the bar 36 and having slots 40 and 41 respectively for receiving the bar, and an eccentric 42 for imparting reciprocatory movement to the bar. The eccentric 42 is secured to the gear wheel 29 and engages the lateral projections or lugs 43 of the bar 36 to impart the reciprocatory motion to the bar.

Referring particularly to Figure 2 it will be seen that with the eccentric in the position shown, the bar has been moved to the left so that the left hand end portion thereof is received in the slot 40 of the fixed support 38, thus holding the cylinder A against rotation. In this position the opposite or right hand end of the bar has been moved clear of the fixed support 39 to leave a

gap 44 between the bar and the support, thus providing an unobstructed passageway for the rotating run of thread T¹ leading from the eyelet of the whorl C to the take-off guide 35 which is mounted in coaxial spaced relation to the end of the cylinder. As the eccentric 42, the gear wheel 29, and the run of thread T¹ continue in their rotation through 180°, the eccentric shifts the bar 36 to the right into the aperture 41 in the fixed support 39 and out of the aperture 40 in the fixed support 38 to leave a gap at 45 between the left end of the bar and the support 38, thus providing an unobstructed passageway for the rotating run of thread T¹. It will be seen from the foregoing that by means of this alternate engagement of the bar 36 with the supports 38 and 39 the cylinder A is at all times positively held against rotation while at the same time providing for unobstructed rotation of the whirling run of thread.

As I have thus far described my invention, the thread is laid up so that the helix of thread is snugly laid on the cage, this being useful for some purposes in the manufacture of cuproammonium rayon in which the freshly spun filaments are laid up on the cage for treatment such as acid washing, water washing and drying.

However, in some cases it is desirable to lay the thread on the cage somewhat loosely so that the successive turns hang as loops, so to speak, the upper portions of the turns being supported and advanced by the thread advancing means of the cage and the lower portions hanging loose. This is particularly useful where it is desired to allow the thread to freely shrink during drying, for example.

Whether or not the thread is wound snugly on the cage and under tension, or loosely, depends upon the tension on the thread being led to and whirled upon the cage. For instance, in the spinning of cuproammonium rayon, the freshly spun filaments, after leaving the setting bath, are passed over a resistance device such as a "Godet" wheel or wheels (not shown), located intermediate the setting bath and the whorl. Thus, tension may be put on the thread, and the amount of tension determines whether or not the helix is snugly or loosely laid up on the cage.

Furthermore, while I have in this instance shown thread supporting and advancing members in the form of cords or cables, the above advantages may be obtained in other non-rotating cages having provision for supporting and advancing the thread in the form of a helix. For example, the supporting and advancing members could be in the form of movable relatively non-flexing bars such as shown in my copending application, Serial No. 332,693, filed May 1, 1940.

I claim:

1. Apparatus for laying up thread in the form of a continuously advancing helix, comprising a non-rotatable support, a thread guide adjacent one end of said support, means for rotating said support around said support to lay thread on said support, means for moving said thread along said support as it is being laid thereon so as to provide a continuously advancing helix of thread on said support, a thread guide adjacent the other end of said support, and means for rotating said second mentioned thread guide in one to one ratio with the first mentioned thread guide to take thread off the support turn for turn of its being laid on the support.

2. Apparatus for laying up thread, comprising a non-rotatable support, a whorl for laying

thread on said support adjacent one end thereof to be advanced to the other end, a whorl for taking thread off said support adjacent said other end, and means for rotating said whorls at one to one ratio, said support having thread supporting surfaces movable in one direction of the length of said support to advance the thread being laid thereon in the form of a continuously advancing helix.

3. Apparatus for laying up thread in the form of a continuously advancing helix, comprising a non-rotatable cage having a plurality of thread supporting surfaces in the form of longitudinally extending circumferentially spaced cords, pulleys over which said cords are guided so that outer runs thereof constitute said supporting surfaces, means for driving said cords with said outer runs all moving at the same rate of speed and in the same direction lengthwise of said cylinder, a whorl for laying thread on said supporting surface adjacent one end thereof to be advanced to the other end, a whorl for taking thread off said supporting surface adjacent said other end, and means for rotating said whorls at one to one ratio.

4. Apparatus for laying up thread in the form of a continuously advancing helix, comprising a cage-like cylinder having thread supporting surface movable in one direction of the length of said cylinder, a whorl for laying thread on said cylinder adjacent one end thereof to be advanced to the other end, a driven wheel to which said whorl is secured for rotation therewith, a whorl for taking thread off said cylinder adjacent said other end, a driven wheel to which said last mentioned whorl is secured to rotate therewith, means for driving said wheels at one to one ratio, means for concentrically mounting said cage-like cylinder with said wheels, means for supporting said wheels adjacent their peripheries, and means for preventing rotation of said cage-like cylinder.

5. Apparatus for laying up thread in the form of a continuously advancing helix, comprising a cage-like cylinder having thread supporting surface movable in one direction of the length of said cylinder, a whorl for laying thread on said cylinder adjacent one end thereof to be advanced to the other end, a driving wheel to which said whorl is secured for rotation therewith, a whorl for taking thread off said cylinder adjacent said other end, a driven wheel to which said last mentioned whorl is secured to rotate therewith, means for driving said wheels at one to one ratio, means for concentrically mounting said cage-like cylinder with said wheels, means for supporting said wheels adjacent their peripheries, and means for preventing rotation of said cage-like cylinder, said last mentioned means including a reciprocating bar mounted at one end of said cylinder crosswise thereof, fixed members at the ends of said bar, means for reciprocating said bar to alternately engage said fixed members and to alternately provide gaps between said bar and fixed members whereby interference with the thread is avoided.

6. In apparatus for laying up thread in the form of a continuously advancing helix, a non-rotating cage-like cylinder comprising a plurality of longitudinally extending circumferentially spaced cords constituting the thread supporting surface thereof, means for guiding and moving said cords at uniform speed in one direction lengthwise of the cylinder, mounting means for said cylinder, a thread laying up whorl adjacent one end of said cylinder, a thread taking off

whorl adjacent the other end of said cylinder, means for rotating said whorls at one to one ratio, a thread guide coaxial with the axis of rotation of said laying up whorl from which the thread is led to said whorl, a thread guide coaxial with the axis of rotation of said taking off whorl through which the thread being taken off the cylinder by the whorl is led, and means associated with the whorl rotating means at one end of said cylinder for holding said cylinder against rotation, said means comprising fixed bracket means, a movable member and means for imparting movement to said movable member to clear the run of thread between the thread guide and the whorl as it rotates while maintaining said movable member in engagement with the fixed bracket means.

7. In apparatus for laying up thread in the form of a continuously advancing helix, a non-rotating cage-like cylinder comprising a plurality of longitudinally extending circumferentially spaced cords constituting the thread supporting surface thereof, means for guiding and moving said cords at uniform speed in one direction lengthwise of the cylinder, mounting means for said cylinder, a thread laying up whorl adjacent one end of said cylinder, a thread taking off whorl adjacent the other end of said cylinder, means for rotating said whorls at one to one ratio, a thread guide coaxial with the axis of rotation of said taking off whorl through which the thread being taken off the cylinder by the whorl is led, and means associated with the whorl rotating means at one end of said cylinder for holding said cylinder against rotation, said means comprising a bar mounted on the cylinder crosswise thereof for reciprocation back and forth, a fixed member located at each end of said bar, means for reciprocating said bar to alternately engage said fixed members and to provide a gap at the member not being engaged for the passage of the rotating run of thread from the guide to the whorl.

8. In apparatus for laying up thread in the form of a continuously advancing helix, a non-rotating cage-like cylinder comprising a plurality of longitudinally extending circumferentially spaced cords constituting the thread supporting surface thereof, means for guiding and moving said cords at uniform speed in one direction lengthwise of the cylinder, mounting means for said cylinder, a thread laying up whorl adjacent one end of said cylinder, a thread taking off whorl adjacent the other end of said cylinder, means for rotating said whorls at one to one ratio, a thread guide coaxial with the axis of rotation of said laying up whorl from which the thread is led to said whorl, a thread guide coaxial with the axis of rotation of said taking off whorl through which the thread being taken off the cylinder by the whorl is led, and means associated with the whorl rotating means at one end of said cylinder for holding said cylinder against rotation, said means comprising a diametral bar mounted on the cylinder for reciprocation back and forth, a fixed member at one end of said bar, a diametrically opposed fixed member at the other end of said bar, and means for reciprocating said bar to alternately engage said members and to provide a gap at the member not being engaged for the passage of the rotating run of thread from the guide to the whorl.

9. In apparatus for laying up thread in the form of a continuously advancing helix, a non-

rotating cage-like cylinder comprising a plurality of cords, pulleys over which said cords are run, said pulleys being arranged to provide a plurality of longitudinally extending circumferentially spaced outer runs of the cords constituting the thread supporting surface of said cylinder, means for driving said cords with said outer runs all traveling at the same speed and in the same direction, supporting structure on which said pulleys and cord driving means are mounted, axle means projecting beyond each end of said cylinder, a driven gear wheel at each end of said cylinder mounted on said axle means, rollers on which the rims of said gears ride to give peripheral support to said cylinder, a thread laying up whorl carried by the gear wheel at one end of said cylinder, a thread guide fixedly positioned beyond said last mentioned gear wheel coaxially therewith through which thread from a source

5 of supply is lead to said laying up whorl, a thread taking off whorl carried by the gear wheel at the other end of said cylinder, a thread guide fixedly positioned beyond said last mentioned gear wheel coaxially therewith through which the thread from the taking off whorl is led, means for driving said driven gear wheels at one to one ratio, and means fixing said cylinder against rotation comprising fixed bracket means at one end of the cylinder, a movable member engaging said bracket means, said member being carried by the axle at said end of the cylinder, and means for moving said member to positions of non-interference with the whirling run of thread between the thread guide and whorl at said end of the cylinder while being maintained in engagement with said fixed bracket means.

10 WILLIAM H. FURNESS.
